UNITED STATES PATENT OFFICE.

AUGUSTINE J. POCOCK, OF DAYTON, OHIO.

DISPENSING-PUMP.

1,244,077.

Specification of Letters Patent. Patented Oct. 23, 1917.

Application filed June 26, 1915. Serial No. 36,443.

To all whom it may concern:

Be it known that I, AUGUSTINE J. POCOCK, a citizen of the United States, residing at Dayton, in the county of Montgomery and State of Ohio, have invented certain new and useful Improvements in Dispensing-Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain improvements in liquid measuring pumps and consists of a single-acting single cylinder pump such as is hereinafter more particularly described. The object of the invention is to materially increase the efficiency and capacity of such type of pump. This is accomplished by reducing to the lowest minimum idleness in various acting parts. For example, the idle stroke of the piston is accomplished at a considerably greater speed than is necessary for the working stroke, to the end that the time necessary in the operation of the pump is economized. This, as well as other advantages, such as a novel and compact arrangement of the driving gears and reversing devices such as cams and clutches, are attained, and thus insure correct quantities at each discharge. These and other objects and advantages will be more or less emphasized in the description to follow.

Referring to the accompanying drawings which illustrate my improved pump in detail, Figures 1 and 2 are vertical side and front elevations of the pump in tact; Fig. 3 is an enlarged sectional view of the lower portion of the pump broken at the middle to facilitate illustration; Fig. 4 is an enlarged sectional view on the line *a—a* of the gear box, showing the reversing driving gears and allied parts; Fig. 5 is a side elevation of the gears and allied parts, the shafts appearing in section; Fig. 6 is an enlarged sectional view of the vacuum breaker; Fig. 7 is a sectional view across the piston cylinder on the line *b—b* of Fig. 3; Fig. 8 is a sectional detail of the discharge regulating devices on the line *c—c* of Fig. 1.

55 In a detail description of the invention, similar reference characters indicate corre-

sponding parts both in the description and drawings.

Referring more particularly to the drawings, 1 designates the pump cylinder casing mounted on a suitable base and opposite sides of which are open to allow access to the interior thereof, said openings in the sides being closed by plates 2—2. The top of said cylinder terminates in a head 28 providing a chamber closed by a cylinder cap 46. The liquid is discharged into said chamber by the upstroke of the piston to be more particularly described hereinafter. The lower portion of said cylinder is provided with a liquid inlet 43 and a cap-closed hand opening 44 through which access may be had to the suction valve hereinafter more definitely described. The piston cylinder 3 is secured between upper and lower flanges 45 and 45', the latter forming the seat for the piston 21. The said cylinder 3 is wrapped by a suitable insulating jacket 4 which may consist of a composition of matter such as cork and a suitable binder which is applied and renewed when necessary through the openings which are closed by the side plates 2. The said jacket is designed to maintain the cylinder at a desirable temperature. The suction valve 25 seats in a suitable opening above the inlet space 24. When not affected by the discharge stroke of the piston 21, the valve 25 has its seat and in order to apply a suitable additional pressure on the valve when seated to maintain an effective seating, a spring 26 is mounted thereon around a suitable projection. A stirrup or frame 23 is secured to the bottom of the piston in a position to engage said spring just as the piston approaches its seat, therefore, the weight of the piston and the parts connected thereto is instrumental in insuring such proper seating of said valve, the spring 26 affording a suitable elastic intervening part. A cylinder inlet or discharge valve 24^x is carried by the piston which opens upon the down-stroke of the piston and closes upon the up-stroke. A rack 8 is suitably connected to the piston rod 22 extended from the piston. This rack is held in mesh with its driving gear by a roller 40. The said rack extends into a gear box 5 which is of suitable character to properly house the driving gears and their allied parts, to be presently described. The gear box 5 is mounted upon the air pipe 30 and discharge pipe 29 both extending from the

cylinder head 28. The rack 8 gears with its driving gear 9 which is pinned to shaft 6 journaled in the top of the gear box 5. The gear 9 is driven in opposite directions by gears 10 and 12 the former of which is mounted on shaft 7 journaled in the gear box 5 and the latter, to-wit, gear 12, is fixed to said gear 9 and to the shaft 6. A pinion 11 also runs on shaft 7 and meshes with the gear 12. The gear 9 is driven in reverse directions by gears 10 and 11 and these are controlled by clutch members 15 and 16 which are fixed, respectively, to said gears. Coöperating with said clutch members 15 and 16 are clutch members 14 and 17, respectively, which are slidable on shaft 7. The outer ends of said clutch members 14 and 17 have each a spiral slot which provide inner and outer cam surfaces 19 and 19' and end abutments 18 and 18'. The clutch members 14 and 17 are slid on the shaft 7 and rotated by double-acting cams or dogs 20 and 20' fixed to said shaft. The sliding or reciprocating movement is imparted by alternate engagements with the inner and outer inclined surfaces 19 and 19' and the rotary movement takes place when said cams engage the abutments 18 and 18'. Means are provided for preventing the clutch members 14 and 17 rotating while the cams 20 and 20' are moving against the inclined surfaces 19 and 19' and until the abutments 18 and 18' are engaged. Such means consist of brake shoes 31 which are arranged to engage the annular surfaces 31' of said clutch members. These friction shoes are suitably mounted on arms 32 that are in turn conveniently mounted on the frame of the pump, as shown in Fig. 5, and connected by a cross bar 32'. Suitable pressure is applied to said shoes by springs 33 which are attached at one end to the arms 32 and the other ends of which have an adjusting connection 34' to a convenient part of the frame. From the foregoing description, it will be seen that the rack 8 and therewith the pump piston are given reciprocatory movement from the gear 9 which is always in engagement therewith, one direction of movement being imparted from the crank handle 35 pinned to shaft 7, clutch members 14 and 15, and gear 10, and the other direction of movement being imparted through clutch members 16 and 17 and gears 11 and 12. Owing to the differential of the gears, the idle stroke of the piston is obtained in a much briefer space of time. The discharge pipe 29 communicates with a chambered head 34 from which the discharge spout 36 extends, which in turn discharges through a hose (not shown). The discharge of the oil or liquid through said spout and hose has a tendency to siphon and to thereby interfere with correct discharges or measurements. Inasmuch, however, as

siphoning cannot occur without what is commonly termed a vacuum at the head of the discharge pipe, I have provided what may be termed a vacuum breaker as a preventive consisting of a diaphragm 37 mounted in the top of the head 34 and having an orifice 38 and a button 39 of suitable material such as leather secured to the cap of said head. By the said diaphragm closing against said button, the exclusion of air from the chamber below takes place, thereby constituting what may be termed an automatic vacuum breaker. The discharge stroke of the piston is regulated through stops 41 arranged at suitable points along a rod 42 mounted between the head 28 and gear box 5. These stops may limit the piston to a one-half gallon, gallon, two gallon, and two and a half gallon stroke, and the rod 42 is turned to bring said stops in or out of alignment with a shoulder 47 on the lower end of the rack 8. Such operation is given said rod 42 by means of a hand rod or bar 48 suitably mounted. When a particular stop 41 is placed in position, it may be locked and sealed in such position. This is accomplished by means of a series of members 49, one connected to each stop 41. The said members 49 have a screw-threaded connection with a rod 50 mounted adjacent to and parallel with the stop rod 42. The said members 49 have each a series of recesses 51 in which a sealing rod 52 lies. This rod may be sealed in any suitable manner. In the drawings I have shown the end thereof projected through an opening in a lug 53 on a side of the screening or filtering case 54.

Having described my invention, I claim.

1. In a pump of the type specified, the combination with a pump cylinder, a piston therein, and a rack connected to the rod of said piston, of an oblong gear box into which said rack projects the upper transverse area of which is less than the transverse area of the lower portion of said gear box, transverse gear shafts mounted in said box, a driving gear mounted on the upper shaft and adapted to drive said rack in one direction, another gear on said upper shaft and adapted to drive the rack gear in a reverse direction, gears on the lower shaft meshing with those on the upper shaft, clutches on said lower shaft members connected to the gears on said lower shaft and the other members of which are slidable on said lower shaft, said slidable clutch members having cam slots terminating in end abutments, and actuating cams fixed to said lower shaft and extending into said slots, said cams being adapted to impart longitudinal and rotary movements to the slidable clutch members to alternately engage and disengage the clutch members on said gears, substantially as specified.

2. In a pump of the type specified, the

- combination with a pump cylinder, a piston therein, and a rack connected to the rod of said piston, of an oblong gear box into which said rack projects the upper trans-
 5 verse area of which is less than the trans-
 verse area of the lower portion of said gear
 box, transverse gear shafts mounted in said
 box, a driving gear mounted on the upper
 shaft and adapted to drive said rack in one
 10 direction, another gear on said upper shaft
 and adapted to drive the rack gear in a re-
 verse direction, gears on the lower shaft
 meshing with those on the upper shaft,
 15 clutches on said lower shaft members which
 are connected to the gears on said lower
 shaft and the other members of which are
 20 slideable on said lower shaft, said loose
 clutch members having cam slots terminat-
 ing in end abutments, actuating projections
 fixed to the lower shaft and extending into
 25 said slots, said projections being adapted
 to impart slideable movement to said clutch
 members by engaging the sides of said slots
 and rotary movement by engaging the end
 abutments of said slots, and friction de-
 30 vices holding said slideable clutch members
 from rotation until the clutches engage, sub-
 stantially as specified.
3. In a pump, the combination with a pis-
 35 ton and a driving rack connected thereto,
 of a main driving gear in mesh with said
 rack and imparting thereto reciprocating
 movement at different speeds, a driving gear
 rotatable on the axis common to the main
 driving gear and adapted to impart one of
- such movements to said rack through said
 main driving gear, a driving gear in mesh
 with said main driving gear and adapted to
 impart to said rack through said main driv-
 40 ing gear a reverse and variable movement
 to said rack, an intermediate gear in mesh
 with the gear which rotates on the common
 axis with the main gear, clutch members
 45 fixed to said intermediate gear and to the
 gear in mesh with said main driving gear,
 and means for alternately imparting slid-
 able movement to said clutch members and
 rotary movement through the rotation of
 50 the shaft upon which said last named gears
 are mounted.
4. In a pump, the combination with a pis-
 ton and a driving rack connected thereto,
 of a main driving gear 9 imparting to said
 rack reciprocating movement at variable
 55 speeds, a gear 12 imparting to said driving
 gear one of said speeds, a non-alined gear
 10 imparting to said gear 9 the other of
 said speeds, a gear 11 in mesh with the gear
 12, fixed and movable clutch members 14
 and 15 for driving the gear 10, fixed and
 60 movable clutch members 16 and 17 for driv-
 ing the gear 11, and cam devices coöperating
 with the movable clutch members to impart
 slideable movement thereto to engage and
 disengage the respective gears 10 and 11 and
 65 to rotate one or the other of such gears
 when engaged.

In testimony whereof, I affix my signature.

AUGUSTINE J. POCOCK.
